UNITED STATES PATENT OFFICE.

ADOLPH C. RECKER, OF OAKVILLE, CONNECTICUT, ASSIGNOR TO THE CHASE COMPANIES, INC., OF WATERBURY, CONNECTICUT, A CORPORATION.

KEY-OPERATED FUSE-PLUG.

1,387,906.

Specification of Letters Patent. Patented Aug. 16, 1921.

Application filed November 10, 1919. Serial No. 336,924.

To all whom it may concern:

Be it known that I, ADOLPH C. RECKER, a citizen of the United States, residing at Oakville, in the county of Litchfield and 5 State of Connecticut, have invented a new and useful Improvement in Key-Operated Fuse-Plugs; and I do hereby declare the following, when taken in connection with the accompanying drawings and the characters of reference marked thereon, to be a full, clear, and exact description of the same, and which said drawings constitute 10 part of this application, and represent, in—

Figure 1, a plan view of a fuse plug embodying my invention.

Fig. 2, a reverse plan view thereof.

Fig. 3, a view in vertical section on the line 3—3 of Fig. 1.

Fig. 4, a view in transverse section on the 20 line 4—4 of Fig. 2.

Fig. 5, a view partly in side elevation and partly in section of one form which an operating-key constructed in accordance with my invention may assume.

Fig. 6, a view in side elevation of the plug and key shown as combined, the former being shown as screwed into its protected position in a plug-receptacle which is shown partly broken away and in section.

My invention relates to an improved key-operated self-protecting fuse-plug of the non-removable fuse type, the object being to produce at a low cost for manufacture, a simple and reliable fuse-plug constructed 35 with particular reference to being so embedded in any standard plug-receptacle when in use, that when its key is removed it is protected against being tampered with and also prevented from being removed sur- 40 reptitiously or to meet an emergency.

With these ends in view, my invention consists in a key-operated self-protecting fuse-plug characterized by its adaptation to be screwed by a removable key into such a 45 position in any standard plug-receptacle that it cannot be removed at will therefrom except by the use of its key or some substitute therefor. My invention further consists in a key-operated self-protecting head- 50 less fuse-plug characterized by having a relatively short fuse and its mica disk located so close thereto as to render the observation of the fuse easy. My invention further consists in certain details of construction and combinations of parts as will 55

be hereinafter described and pointed out in the claims.

In carrying out my invention as herein shown, I construct what may be aptly termed a half-plug or headless plug inasmuch as it is made considerably shorter than the ordinary plug and entirely lacks the finger-grip by which the ordinary fuse-plug is screwed into place in a plug-receptacle and removed therefrom. My improved fuse-plug as compared with fuse-plugs of the prior art has a relatively short cylindrical body 5 of porcelain or other insulating material, its outer end being substantially flat and its inner end being slightly conical. 60 This body is mounted in a threaded screw-shell 6 somewhat shorter than the axial length of the plug-body 5 and having its inner portion threaded. At its inner edge the said shell is formed with an inwardly turned narrow assembly-flange 7, overlapping the edge of the conical inner end of the plug-body which is held against rotation within the shell by its provision with a tangential notch or cut 8 receiving a flat-face 9 formed as a part of the assembly-flange 7 as shown in Fig. 2. The outer end of the shell 6 is formed with an inwardly turned annular retaining-flange 10 which overlaps the edge of a mica window 11 in 65 the shape of a disk which is thus held directly against the flat outer end or face of the plug-body 5 as shown in Figs. 1 and 4.

The plug-body is traversed by a central fuse-chamber 12 entering its outer end and terminating near the apex of its cone in a concentric rivet-hole 13 receiving the prongs 14 of a contact-rivet 15 of some other type such as a standard tubular rivet. The prongs 14 not only serve to hold the contact-rivet 15 in place but also for the attachment of the inner end of the fuse 16, the outer end of which lies upon or close to the inner face of the mica window 11 and extends between the same and the flat outer 100 face of the plug-body, its outer extremity being let into a recess 16^a in the edge thereof so as to extend under and make contact with the side wall of the screw-shell 6. The outer portion of the fuse is thus brought 105 close to the mica-window 11 and therefore so close to the exposed outer end of the plug that when the fuse is "blown out" it invariably smokes the face of the window and discloses to even casual observation that the 110

plug is "dead," whereas in the fuse-plugs of the prior art, the fuse is located so far away from the outer end of the plug and so far away from the mica-window that the 5 fuse does not invariably smoke the window when "blown out," leaving the fact to be determined only by a close examination of the plug or even the testing of the same.

10 I am able to employ a short, headless or half-plug as described, by providing for its insertion and removal by an operating-key 15 made of insulating material and consisting of a hub 17 substantially corresponding in diameter to the diameter of the plug-body 5 and furnished at its outer end with a knurled flange 18. From the inner end of the hub 17 project slotted key-prongs 19 formed by the projecting ends of a wire loop 21 embedded in the hub 17 when the same is 20 molded.

For the reception of the slotted key-prongs 19, the plug-body 5 is formed in its outer face with two key-holes 22 located on opposite sides of the fuse-hole 12 and made 25 accessible through corresponding holes 23 in the mica window 11 which is prevented from turning within the flange 10 so as to obstruct the holes 22, by the formation upon the outer face of the plug body 5 of two 30 integral annular bosses 24 concentric with the key-holes 22, the holes 23 in the mica window being large enough to fit over the said bosses 24, whereby the mica window is prevented from turning.

35 My improved self-protecting headless half-plug is screwed by its removable key into a plug-receptacle screw-shell 25 located within a sleeve 26 projecting from the face of a receptacle-block 27 of any approved 40 construction and design. The receptacle screw-shell 25 has a contact 28 to which the terminal strip 29 leads. My improved half-plug is proportioned in overall length to the length of the screw-shell 25 of a standard 45 fuse-receptacle so that when the plug is screwed into place as described its outer end will be substantially flush with the end of the sleeve 26 thereof as shown in Fig. 6, whereby when its key is withdrawn, the fuse- 50 plug is protected against being tampered with and against removal except with its own key or at some considerable trouble for the improvisation of a key which will answer the purpose. Constructing the plug so 55 that it can only be removed without considerable trouble except by its own key, the plug is protected against removal by an unauthorized person and replacement by a plug of higher capacity is thus guarded 60 against. By preference but not necessarily, the key-prongs 19 are slotted to give the prongs 19 sufficient resiliency for their retention in the key-holes 22 in the plug-body 5 in case it is desired to leave one key in the 65 fuse block. So also, if the fuse-receptacle is

in the ceiling, a key having resilient prongs would not drop out by gravity. Ordinarily the key will be removed and kept in a safe place to prevent tampering with the plugs.

The shortness of my improved headless 70 plug materially cheapens it over the longer plugs of the prior art so that in discarding the plug when it is "dead," there is much less loss, the item of expense chargeable to "dead" plugs being therefore less with my 75 improved plug than with the non-removable fuse-plugs of the prior art. The key provided with my half-plug may, of course, be used indefinitely. I do not limit myself to the employment of any one key as it is obvious that the form shown may be varied, my invention in this respect being characterized by a headless-plug adapted to be operated by a removable key of whatever character and design. 80

I claim:

1. A removable, key-operated, headless, screw fuse-plug comprising a headless plug-body having a fuse-chamber, a screw-shell in which the said body is mounted, a fuse located within the said chamber, and making contact at its outer end with the said shell, a contact located at the inner end of the body for the inner end of the fuse, and a mica window closing the outer end of the 95 said fuse-chamber, the said body being adapted in length to substantially fit within the screw-shell of a standard receptacle, and being manually removable by means of a removable key. 100

2. A removable, key-operated, headless, screw fuse-plug comprising a headless plug-body having a fuse-chamber, a screw-shell in which the said body is mounted, a fuse located in the said chamber, and a mica window closing the outer end of the said chamber, the said body being also provided with two parallel key-holes located on opposite sides of the said fuse-chamber for the simultaneous reception of members of a removable key by means of which the plug structure is screwed into and out of the screw-shell of a standard screw-shell receptacle 110 within which it fits.

3. A removable, key-operated, headless, screw fuse-plug having a plug-body formed with a fuse-chamber and with two key-holes located on opposite sides thereof and surrounded at their outer ends by concentric bosses, a screw-shell in which the said body 120 is mounted, a fuse located in the said chamber, and a mica window closing the outer end of the said fuse-chamber and formed with holes fitting over the said bosses, whereby the mica window is prevented from 125 rotation and thus obstructing the said key-holes, the said body being adapted in length to substantially fit within a standard screw-shell receptacle into and out of which it is screwed by means of a removable key. 130

4. The combination with a removable, key-operated, headless, screw fuse-plug adapted in length to substantially fit within the screw-shell of a standard screw-shell receptacle, and having a plug-body formed with a fuse-chamber and with two key-holes located on opposite sides thereof; of a removable key comprising a flanged-hub of insulating material, corresponding substantially in diameter to the diameter of the said plug-body, and embedding a wire loop the ends whereof project from its inner end in which they are separated by the distance separating the key-holes in the headless plug-body.
5. A removable key for a removable, key-operated, headless, screw fuse-plug, the said key comprising a flanged-hub of insulating material, embedding a loop-shaped wire the ends of which project from the said hub, and are slotted for insertion into key-holes in the body of a removable fuse-plug.
- In testimony whereof, I have signed this specification in the presence of two subscribing witnesses.

ADOLPH C. RECKER.
